UNITED STATES PATENT OFFICE.

RICHARD WHARTON, OF PHILADELPHIA, PENNSYLVANIA, ASSIGNOR OF
ONE-HALF TO WILLIAM WHITAKER, OF SAME PLACE.

THREAD GUIDE AND TENSION DEVICE.

SPECIFICATION forming part of Letters Patent No. 272,812, dated February 20, 1883.

Application filed July 3, 1882. (No model.)

To all whom it may concern:

Be it known that I, RICHARD WHARTON, a subject of the Queen of Great Britain, residing at Philadelphia, in the State of Pennsylvania, have invented a new and useful Improvement in Thread Guide and Tension Devices, of which the following is hereby declared by me to be a full, clear, and exact description.

The object of my invention is to provide accurately operating means whereby thread or yarn can be compactly and smoothly wound or wrapped upon bobbins, and be moreover so wrapped as to assume a proper predetermined exterior contour.

15 In the winding of thread upon bobbins it is the practice to affix the bobbin to a spindle or kindred device, which will impart to it a rapid rotary motion, and to feed the thread to said rotating bobbin from a spool by means of 20 thread-guides or the like, through which the thread is passed in its path from the spool to the bobbin, said thread-guides being mounted upon a reciprocating traverse-bar, by which they are reciprocated lengthwise of the bobbin, with the result that an even distribution 25 of the thread from end to end of the bobbin is secured.

As will be readily understood, in the winding of bobbins, when it is desired to supply 30 more thread at one portion than at another, it is of advantage to have the thread regulated by some tension which will enable its rapid or slow feed without occasioning it to be either too loosely or too tightly wrapped upon said 35 portions of the bobbin.

In the accompanying drawings, which represent a thread guide and tension device conveniently embodying my invention, Figure 1 is a view of the same in front elevation, showing also a portion of a bobbin. Fig. 2 is a view of the same in side elevation, showing both the bobbin and feed-spool. Fig. 3 is a vertical longitudinal central sectional elevation of my thread guide and tension device. Fig. 4 is an 45 end elevation of the same, a portion of one of the barrel-heads being broken away to exhibit one of the brake-springs. Fig. 5 is an end elevational view looking from the inside of one of the barrel-heads referred to. Fig. 6 is a central vertical sectional detail of a modified construction, hereinafter fully explained.

In all of the above figures similar letters of reference indicate corresponding parts, and said figures represent a preferred form of a convenient embodiment of the invention.

55

In the drawings, A is a traverse-bar, supposed to be constructed and to operate in the usual manner. It is but partially shown.

B is a bracket or standard erected from the traverse-bar and adapted to fixedly retain and support the shaft of my thread guide and tension device.

C is the central shaft, fixedly connected to the bracket referred to, and branching off horizontally therefrom. The central portion of the 65 shaft, to which the letter C is applied, and which is well exhibited in Figs. 3 and 6, is round, while on either side of said rounded portion the shaft is squared, as at c, or otherwise formed of irregular contour to fit it, to receive 70 and hold in such position that they cannot rotate the fixed inclosing-barrels D. These barrels are well made when of the form represented in the sectional view of Fig. 3—that is to say, they are cap-like devices adapted to inclose and contain certain of the working parts of the device. They are each cylindriform in exterior contour, and are internally divided into two cavities—an inner cavity, d, and an outer cavity, d'—which are divided from each 80 other by a diaphragm, E, through the medium of which the barrels are secured to the squared ends c of the shaft.

F are what I term "tension-caps," a convenient form of which is represented in Figs. 85 1 and 3. They are of similar construction and oppositely placed, so as respectively to cover and inclose the open end of the larger cavities of the barrels. Centrally they are provided with circular openings of sufficient size to permit them to surround a tubular sleeve, G, which is snugly fitted free for revolution upon the central shaft. The tension-caps are capable of an endwise motion, the one apart from the other, upon the sleeve, but are prevented from rotating independently of the sleeve by reason of the application of cap-springs, as hereinafter more fully explained. As will be observed by a reference to Fig. 3, when the tension-caps have been mounted upon the 90 tubular sleeve, the tubular sleeve has been mounted upon the central shaft, and the in- 95 100

closing-barrels likewise mounted thereupon, the open outer faces of the tension-caps overlap the open inner faces of the inclosing-barrels, and the sleeve, shaft, and other devices hereinafter described are not only completely inclosed, and hidden from view, but likewise protected from dirt, filaments of yarn, and the like.

Erected upon and fixedly connected with the tubular sleeve G at both of its ends are "spring-cups," as I term them, or cylindric inclosing-cups, as they really are, which partially inclose spiral springs I, which surround the tubular sleeve, and are hereinafter termed the "cap-springs." One end of each of these springs is connected to the interior face of one of the tension-caps, and the other to the interior of the spring-cups, or it may be to the tubular sleeve itself. The spring-cups form in effect a part of the tubular sleeve, the construction represented being one of mechanical convenience; and it will be obvious to any mechanic that the operation of the cap-springs which is to retain the tension-caps tightly together, and yet enable their movement lengthwise apart upon the tubular sleeve, would be equally well subserved by connecting these springs, upon the one hand, to the caps, and on the other hand to the sleeve itself, or to any collar or other member, not being the specific spring-cup recited, erected from and connected to said sleeve.

The connection between the cups and the sleeve may be effected by keys, set-screws, or other convenient devices. In the drawings the connection is represented as effected by the jamming of the cups upon the sleeve, which is a convenient method.

From the foregoing description it will be readily understood that whereas the central shaft and the inclosing-barrels are fixed, the tubular sleeve, spring-cups, and tension-caps are free to rotate together with respect to and about the central shaft, while the tension-caps are likewise adapted, in addition to their motion of rotation, for endwise movement upon the sleeve.

J, Fig. 2, is a spool off from which the yarn is to be unwound and wound upon the bobbin K. The bobbin is actuated from any suitable spindle, L, or actuating-shaft. The yarn is carried from the spool between the tension-caps to the bobbin. Motion being imparted to the bobbin and to the traverse-bar, it will be readily understood that the thread is wound upon the bobbin after having been drawn between the tension-caps.

The strength of the cap-springs I is intended to be such as to render a very nice and exact endwise movement of said caps possible, and the thread is controlled or held between the caps in the manner, for instance, of a sewing-machine tension.

Under ordinary circumstances the device as above recited is complete and operative. I have, however, devised a means whereby, in addition to the above control had by the tension-

caps upon the thread, a very perfect control exterior to said caps can be obtained. This means is a brake, M, consisting of a cross-bar, to which the letter M is applied, provided with two arms, m, as shown in Figs. 1 and 2, the said arms being pivoted at N to the respective barrels, which are preferably slotted through at O for the fitting of the brake when the latter is made of the form and attached in the manner represented in the drawings.

In the outer cavities, d', of the barrels are applied spiral band-springs S, called herein the "brake-springs," which are rigidly connected at their inner extremities to the barrel-heads P, which latter are adjustably fitted to the ends of the barrels, so as to tightly inclose their outer cavities, while the outer extremities of the springs are connected—as, for instance, by means of the pins Q—to the said arms of the brake. These brake-springs, being coiled in the outer cavities, in their passage out to the brake, pass through openings R in the barrels. The inner extremities of these brake-springs being attached to the barrel-heads, the springs are adapted to be tightened up by the rotation of the heads and the tightening of the latter against the outer face of the barrels by means of the lock-nuts I, which are threaded upon the shaft. By this means a greater or less tension can be given to these springs, and consequently to the brake, which is dependent upon them for its tension.

The brake being, both as to its controlling-springs and as to its pivots, connected with the stationary barrels and independent of the tension-caps, it is obvious that it can be employed as a separate tension device to co-operate with the tension-caps in their action upon the yarn.

The yarn, after passing through between the tension-caps, passes over and against the brake in the manner represented in Figs. 1 and 2, and according to the set of the brake-springs—that is, whether they be tightly or not tightly wound—will be the consequent tension which the brake will exert upon the yarn.

The combined control of the tension-caps and brake is such as to effect a very nice and exact control of the thread, and enable its wrapping upon the bobbin without irregularity or looseness at portions of the coil.

The device is of course applicable where, in place of being spooled, the yarn is in hanks.

It is obvious that the barrels could be dispensed with and the device remain operative; yet, apart from the convenience of the construction, the part which the barrels play in excluding dirt and dust from the working parts and in protecting the yarn from oil, should oil be applied, is an important one.

Other devices than the brake-springs may be applied for the control of the brake and other substitutes for the cap-springs. Thus, for instance, in Fig. 6, I have represented as a spring a tubular rubber thimble, U, formed with collars V and fitted around the sleeve, which holds together the tension-caps, and yet

permits of their separation under stress of the thread.

Various minor mechanical changes in the adjustment and relationship of the parts can 5 be made, which will not vary the result had in view.

Having thus described my invention, I claim as an improvement in bobbin-winders—

1. The combination of a fixed shaft supported from and reciprocated by a traverse-bar, a traverse-bar, two tension-caps adapted both to rotate and to move endwise with respect to said shaft, and a friction-brake connected as to its fulcrum with said shaft and free to move from and toward the tension-caps, substantially as described.

2. In combination with a fixed shaft connected with and adapted to be reciprocated by a traverse-bar, a traverse-bar, a tubular sleeve 20 adapted to rotate upon said shaft, two tension-caps adapted both to rotate and to move endwise with respect to the central shaft, and means for both retaining the tension-faces of

the caps in contact and for permitting the endwise movement of said caps apart, the one 25 from the other, substantially as described.

3. In combination with a fixed central shaft, two barrels rigidly connected therewith, a brake pivoted to the barrels and connected therewith by means of spiral band or other 30 springs fastened to the barrels on the one hand and to the brake on the other, substantially as described.

4. The combination of the shaft, tension-caps, cap-springs, brake, and brake-springs, 35 substantially as set forth.

5. In combination, the tubular sleeve, tension-caps, spring-cups, and cap-springs, as and for the purpose specified.

In testimony whereof I have hereunto signed 40 my name this 18th day of May, A. D. 1882.

RICHARD WHARTON.

In presence of—

J. BONSALL TAYLOR,
JOHN JOLLEY, Jr.
